[57] **ABSTRACT**

Certain groups of adjacent warp yarns are at times fed to the circular warp knitting machine at a different rate than the remaining groups of warp yarns to thereby vary the length of the stitch loops being formed and to fashion the tubular fabric while it is being knit. Pairs of warp yarn feeding rolls are drivingly interconnected and are arranged around the needle cylinder. One pair of rolls may be selectively driven at a different speed, relative to the other rolls to at times feed a selected group of warp yarns at a different rate and to at times feed all the warp yarns at the same rate.

YARN FEEDING METHOD AND APPARATUS FOR CIRCULAR WARP KNITTING MACHINES

The present invention relates generally to a warp yarn feeding method and apparatus for circular warp knitting machines of the type adapted to produce tubular fabric for use as hosiery, panty hose, and the like, and more particularly to a positive yarn feeding means which may be operated to feed certain groups of adjacent warp yarns at different rates from the remaining warp yarns to thereby form stitch loops of different lengths in selected courses and to fashion the tubular fabric while it is being knit.

As disclosed in my U.S. Pat. No. 3,511,062, issued May 12, 1970, and my copending application Ser. No. 773,995, filed Nov. 7, 1968 now U.S. Pat. No. 3,570,268, the warp yarns are divided into separate groups which are positively fed to the needles by pairs or sets of feed rolls arranged around the needle cylinder. The sets of feed rolls are each driven at the same rate so that all the needles form the same size stitch loop in any given course. While it is possible to change the rate of feed of all the yarns as successive courses are knit, it is not possible to vary the rate of feed of a selected group of yarns to change the size of stitch loops formed by a particular group of needles. Thus, with this type of yarn feeding arrangement, it is not possible to knit a curved tubular fabric or to knit one or more enlarged pockets long one side of the tubular fabric.

With the foregoing in mind, it is an object of the present invention to provide a method and apparatus for positively feeding yarns to a circular warp knitting machine whereby the tubular fabric may be curved while it is being knit or may be knit with one or more enlarged pockets along one side.

In accordance with this invention, means is provided for selectively varying the rate of feed of a certain group of adjacent warp yarns so that stitch loops of different lengths are knit in the same course. In a preferred embodiment of the invention, the yarn feeding means comprises drivingly interconnected sets of positive feed rolls supported around the needle cylinder with a speed-change mechanism interposed between certain sets of the feed rolls so that the rotational speed of certain sets of the feed rolls may be varied at selected times during the knitting of the tubular fabric.

Some of the objects of the invention having been stated, other objects will appear as the description proceeds when taken in connection with the accompanying drawings, in which

FIG. 1 is an isometric view of the upper portion of a circular warp knitting machine with the yarn feeding means of the present invention applied thereto;

FIG. 2 is an enlarged fragmentary isometric view looking in the direction of the arrow 2 in FIG. 1 and illustrating a speed-change mechanism interposed between adjacent sets of feed rolls;

FIG. 3 is an enlarged fragmentary plan view of the speed-change mechanism shown in FIG. 2, with parts in section to illustrate the manner in which the bevel gears may be selectively engaged to vary the feed rate of adjacent feed rolls;

FIG. 4 is an isometric view of one type of tubular fabric which may be knit in accordance with the present invention; and

FIG. 5 is a view similar to FIG. 4 but schematically illustrating another type of tubular fabric which may be knit in accordance with the present invention, and including an enlarged pocket on one side.

As illustrated in FIG. 1, the circular warp knitting machine includes a main base plate or bed plate 10 which supports a needle cylinder 11 in a fixed position. Latch needles 12 are supported for simultaneous vertical movement in the needle cylinder 11 and adapted to receive and form stitch loops of warp yarns which are divided into separate groups or sets, indicated at W-1 through W-4. The warp yarns are fed to the needles 12 through one or more suitable yarn guide rings, only one of which is shown at 14 in FIG. 1.

Means for positively feeding the different groups of warp yarns to the feed rolls at varying rates and to thereby vary the size of stitch loops being formed by the corresponding groups of needles is illustrated in connection with the circular warp knitting machine shown in FIG. 1. This warp yarn feed means generally includes four sets of feed roll means, broadly indicated at A, B, C, and D. However, it is to be understood that a greater or lesser number of feed roll means may be supported around the needle cylinder 11 for separately feeding greater or lesser numbers of groups of adjacent warp yarns to the needles 12.

Each of the feed rolls means A—D includes an upper feed roll 16 and a lower feed roll 17 which are suitably supported for rotation at opposite ends in vertical support posts 18 and 19, fixed at their lower ends on the bed plate 10. The upper feed roll 16 is preferably urged downwardly against the lower feed roll 17 by any suitably resilient means, such as compression springs 20, their lower ends riding on suitable bearing blocks and their upper ends being engaged by spring adjustment means in the form of screws 21 (FIG. 2).

The drive means for rotating the feed roll means A—D includes a one-way drive clutch 21 which is fixed on one end of the drive shaft of the lower feed roll 17 of the feed roll means A (FIG. 1). The inner end of an operating arm 22 is connected to the one-way drive clutch 21 and its outer end is suitably connected to the upper end of a vertically reciprocating rod 23. The rod 23 is moved upwardly and downwardly in tied relationship to operation of the knitting needles and to operation of the machine by any suitable rotating cam or the like on the knitting machine, not shown. Thus, step by step movement is continuously imparted to the lower feed roll 17 of the feed roll means A while the machine is operating.

The opposite end of the drive shaft of the lower feed roll 17 of the feed roll means A is provided with a bevel gear 25 which mates with the same size bevel gear 25 fixed on the drive shaft of the lower feed roll 17 of the feed roll means B. Adjacent ends of the drive shafts of the lower feed rolls 17 of the feed roll means B and C are drivingly interconnected by a pair of bevel gears 26, 27 which are the same size. The lower feed rolls 17 of the feed roll means C and D are drivingly interconnected by a speed-change mechanism, broadly indicated at 30.

The speed-change mechanism includes a first pair of bevel gears 31, 32 of different sizes (FIGS. 2 and 3) fixed on drive shaft 33 of the lower feed roll 17 of the feed roll means D. A second pair of different size bevel gears 34, 35 are supported for free rotation on drive

shaft 36 of the lower feed roll 17 of the feed roll means C and are held on the shaft to prevent longitudinal movement by respective collars 40, 41 which are in turn fixed on the drive shaft 36. The inner hub portions of the bevel gears 34, 35 (FIG. 3) are provided with beveled drive teeth which are adapted to be engaged by the mating driving teeth on opposite sides of a shifting driver 43. The shifting driver 43 is keyed to the drive shaft 36 and may move longitudinally between the position shown in FIG. 3, where it is drivingly engaged with the larger bevel gear 34, and a position where it is drivingly engaged with the smaller bevel gear 35.

A shifting control arm 44 engages the shifting driver 43 at one end and the medial portion is supported for sliding movement in an upstanding support bracket 45. The opposite end of the arm 44 is connected to the upper end of a pattern control link 46, the lower end of which is suitably connected to a pattern control mechanism on the knitting machine, such as a pattern drum, not shown.

METHOD OF OPERATION

In order to knit a curved tubular fabric F, such as schematically illustrated in FIG. 4, the shifting driver 43 is moved to the position shown in FIGS. 2 and 3 so that the drive shaft 36 of the lower feed roll 17 of the feed roll means C is drivingly connected to the drive shaft 33 of the lower feed roll 17 of the feed roll means D by means of the relatively large bevel gear 34 and the bevel gear 32. Then, as knitting of the tubular fabric proceeds, the groups of warp yarns W-1, W-2 and W-3 are all fed to the needles 12 at the same rate of speed and by means of the one-way clutch element 21 and the sets of bevel gears 24, 25 and 26, 27.

At the same time, the group of adjacent warp yarns W-4 is fed to the needles 12 at a faster rate to produce enlarged or elongated stitch loops in this portion of each course of the fabric and to thereby impart the curved configuration to the tubular fabric F, as schematically illustrated in FIG. 4. Since the driving bevel gear 34 is much larger than the driven bevel gear 32, one rotation of the gear 34 will impart approximately two rotations to the bevel gear 32 so that the group of warp yarns W-4 is fed at a much faster rate than the remaining groups of adjacent warp yarns W-1 through W-3. Thus, the group of adjacent needles which knits the warp yarns W-4 forms longer or looser stitch loops than the corresponding groups of adjacent needles which knit the warp yarns W-1 through W-3.

The tubular fabric F (FIG. 4) has been divided into quadrants by dash-dot lines to illustrate the sections of the fabric F which are knit by the groups of adjacent warp yarns W-1 through W-4. One walewise extending quadrant 50 of the fabric F is knit by the warp yarns W-4 which are fed at a much faster rate than the remaining groups of warp yarns so that this quadrant of the fabric is longer than the remaining three quadrants to impart a curved configuration to the fabric.

In order to knit a tubular fabric F', such as schematically illustrated in FIG. 5, having one or more enlarged pockets 51 therein, the shifting driver 43 is selectively moved between the position shown in FIGS. 2 and 3 and a position where it drivingly engages the smaller bevel gear 35. To knit a substantially straight tubular section of fabric, with all sets of warp yarns being fed at

the same rate, the pattern mechanism moves the control link 46 outwardly to impart outward movement to the control arm 44 and shift the driver 43 so that its drive teeth engage the driving teeth on the hub of the smaller bevel gear 35 to thereby drivingly connect this bevel gear 36 with the drive shaft 36 of the lower feed roll 17 of the feed roll means C. Thus, the drive shaft 33 of the lower feed roll 17 of the feed roll means D is driven at the same rate as the drive shaft 36 of the feed roll means C, by means of the driving connection between the same size bevel gears 31, 35. This equal feeding of the sets of warp yarns continues down to the dash-dot line 52 in FIG. 5, where knitting of the enlarged pocket 51 is to begin.

The pattern control means, not shown, then operates to move the shifting driver 43 to the position shown in FIG. 3 and to thereby drivingly connect the large bevel gear 34 with the drive shaft 36 so that the drive to the drive shaft 33 is through the smaller bevel gear 32 and the drive shaft 33 and the lower feed roll 17 of the feed roll means D rotates at a faster rate than the lower feed rolls 17 of the feed roll means A—C. Thus, the group of adjacent warp yarns W-4 is fed at a faster rate during the knitting of the tubular fabric F' from the dash-dot line 52 to the dash-dot line 53 to thereby form the enlarged pocket 51 in one quadrant of the fabric.

Upon completion of the knitting of the tubular A—F' down to the dash-dot line 53, the shifting driver 43 is again shifted into engagement with the driving teeth of the bevel gear 35 so that the driving connection between the drive shaft 36 and the drive shaft 33 is by means of the same size bevel gears 31, 35 and the lower feed roll 17 of the feed roll means D is driven at the same rate as the lower feed rolls 17 of the other feed roll means A—C. Since all of the feed roll means A—D are then driven at the same rate, a straight portion of tubular fabric is knit, until it is desired to knit another pocket in the fabric.

While the warp yarn feeding method and apparatus disclosed in the present application is shown as being operable to increase the feed rate of one group of adjacent warp yarns, it is to be understood that this feeding apparatus may be utilized to vary the feeding rate of more than one group of adjacent warp yarns, if desired. For example, the speed-change mechanism 30 may be positioned between the feed roll means A and B so that the feed roll means B, C, and D operate at a faster rate than the feed roll means A. Also, the speed-change mechanism 30 may be positioned between the feed roll means B and C so that the feed roll means C and D operate to feed the warp yarns at a faster rate than the feed roll means A and B.

Thus, the present yarn feeding method and apparatus is selectively operable to at times feed one or more groups of adjacent warp yarns at a different rate from the remaining groups of adjacent warp yarns, and to at other times feed all of the warp yarns at the same rate. This variation in feed rate of the warp yarns thus permits different types of fashioning or shaping of the tubular fabric to take place while it is being knit.

In the drawings and specification there has been set forth a preferred embodiment of the invention and although specific terms are employed, they are used in a generic and descriptive sense only, and not for purposes of limitation.

I claim:

1. In a circular warp knitting machine including a needle cylinder with needles supported for simultaneous vertical movement therein, the combination therewith of means for positively feeding a certain group of warp yarns to the needles at one rate and another group of warp yarns at a different rate to thereby vary the size of stitch loops being formed by the corresponding groups of needles, said positive feed means comprising a plurality of yarn feed roll means surrounding said needle cylinder and adapted to each feed a group of adjacent warp yarns to a corresponding group of adjacent needles, drive means for rotating said feed roll means, and pattern control means for selectively controlling the rate of feed of at least one of said feed roll means to be identical with or different from the rate of feed of the remaining feed roll means.

2. An apparatus according to claim 1 wherein each of said feed roll means comprises upper and lower feed rolls with the warp yarns passing therebetween, and including resilient means urging said upper roll toward said lower roll.

3. An apparatus according to claim 1 wherein said drive means comprises means for imparting step by step movement to said feed roll means, and means drivingly connecting adjacent feed roll means, and wherein said driving connection between adjacent feed roll means includes a speed-change mechanism said one feed roll means and an operable by said pattern control means.

4. An apparatus according to claim 3 wherein said speed-change mechanism comprises a first pair of bevel gears of different sizes fixed on the driving shaft of said one feed roll means, a second pair of bevel gears of different sizes freely rotatable on the driving shaft of said adjacent feed roll means, and a shifting driver supported between said second pair of bevel gears and being rotated with the driving shaft of said adjacent feed roll means, said driver being movable along said shaft by said pattern control means to drivingly connect one or the other of said bevel gears of said second pair to said shaft.

5. A method of positively feeding warp yarns to a circular warp knitting machine including a needle cylinder with needles supported for simultaneous vertical movement therein, said method comprising the steps of positively feeding all of the warp yarns at the same rate to produce a straight section of tubular fabric, feeding a group of adjacent warp yarns to a corresponding group of adjacent needles at said same rate to form stitch loops of a predetermined size, and while feeding the remaining warp yarns to corresponding needles at an increased rate to enlarge the size of stitch loops being formed by corresponding needles and to thereby form an enlarged pocket in said tubular fabric, and then again feeding all of the warp yarns at said same rate to produce a straight section of tubular fabric.
